(57) **CLAIM**

The ornamental design for a POS terminal, as shown and described.

DESCRIPTION

FIG. 1 is a perspective view of a POS terminal, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged detail view of a portion taken from reference “8” on FIG. 1.

In the drawings, the broken lines depict portions of the article that form no part of the claimed design. The dash-dot-dash broken lines define the enlargement regions and form no part thereof.
